UNITED STATES PATENT OFFICE.

JOSEPHUS J. SUTPHEN, OF WASHINGTON, DISTRICT OF COLUMBIA.

ATTACHMENT FOR BRIDLES.

SPECIFICATION forming part of Letters Patent No. 293,108, dated February 5, 1884.

Application filed June 21, 1883. (No model.)

To all whom it may concern:

Be it known that I, JOSEPHUS J. SUTPHEN, a citizen of the United States, residing at Washington, District of Columbia, have invented 5 certain new and useful Improvements in Attachments for Bridles; and I do declare the following to be a full, clear, and exact description of the invention, such as will enable others skilled in the art to which it appertains to 10 make and use the same, reference being had to the accompanying drawings, and to the letters and figures of reference marked thereon, which form a part of this specification.

The importance of having a taut line in constant driving as well as in speeding horses is 15 known to all horsemen; also, that the pleasure of driving and the value of spirited fast steppers is greatly reduced by reason of tenderness in the mouth, resulting in soreness, 20 which not unfrequently amounts to torture.

I am aware that remedies have been unsuccessfully used for hardening the mouth; also, that the reins have been connected to the bit by a coiled spring, which, in drawing upon the 25 reins, secures a yielding and constant pull upon the bit, and when the elasticity of the spring has been overcome the reins then pull directly upon a strap that passes around the nose. My device possesses advantages over 30 the one described in several points, among which may be mentioned that even in ordinary driving the pull is made upon the nose, no friction being produced until the elasticity of the nose-band is overcome, after which all draft 35 upon the reins comes upon the bit, which would be required in the event of the horse becoming frightened or running away. In the devices heretofore invented, after a certain resistance in the springs is overcome the draft is 40 then upon the nose, which would leave the occupants of the vehicle at the mercy of a frightened horse. Not only does my device give great relief to the horse, but is also safer, cheaper, and more durable.

45 Referring to the drawings, Figure 1 is a perspective view, showing my device in position for use. Fig. 2 is a detail view of the nose-band inclosed in a sheath. Fig. 3 is a detail view of the same broken off near the ends; and

Fig. 4 is a section taken on line $\alpha\alpha$ of Fig. 1, 50 showing the nose strap or band and reins fastened to the rings.

In carrying out my invention, I employ the nose-strap A, which consists of an elastic part, to the ends of which are securely attached the 55 straps a' , adapted to pass through the rings B B' and buckle, as shown at b, and an inclosing-sheath, A', the object of which is to prevent the elastic part of the band from chafing the nose and to exclude moisture, &c. The 60 sheath may be made of leather or material impervious to moisture, preferably sewed or otherwise secured at the center, as shown at b², Fig. 2, to the elastic band. A strap, c, serves to hold the nose-band in proper position to prevent interfering with the horse's breathing, which would otherwise be the case. The strap c can be fastened at its upper end to any suitable part of the bridle. The strap 65 b buckles around both rings, B and B', and the 70 reins are fastened in a like manner. The strap b is drawn up, so as to bring the ring B' forward and permit it to be drawn back somewhat before the draft is communicated to the bit-ring B.

75 I am aware that changes in the form and proportion of the parts composing my invention may be made without departing from the principle or sacrificing the advantages thereof—as, for instance, the elastic band need not 80 extend across the nose, but may be confined to the sides thereof, in which case the sheath may be dispensed with.

Having thus fully described my invention, what I claim, and desire to secure by Letters 85 Patent, is—

1. In a bridle, a nose-strap having an elastic section which is connected to a bit-ring and a supplemental ring, said elastic strap adapted to be passed over the upper jaw of 90 the animal, in combination with reins which are connected to said rings, whereby a primary pull upon the reins comes upon the nose and a secondary pull upon the bit, as and for the purposes set forth.

95 2. In a bridle, a nose-strap having an elastic section inclosed in a sheath, which is connected to a bit-ring and a supplemental ring,

in combination with the reins, whereby a primary pull upon the reins comes upon the nose-band and a secondary pull upon the bit, as and for the purpose set forth.

5. 3. The combination of the nose-strap enclosed in a sheath, rings B B', straps *b* and *c*, in combination with the reins, as and for the purpose set forth.

In testimony whereof I affix my signature in presence of two witnesses.

JOSEPHUS J. SUTPHEN.
